PAPER GUIDE DEVICE

Loring Pickering Crosman, Maplewood, N. J., assignor to Gardner Company, Orange, N. J., a corporation of Delaware

Application October 2, 1935, Serial No. 43,144

1 Claim. (Cl. 197—127)

The invention has relation to paper guide devices, designed to be applied to listing calculators, typewriters or the like.

It has been found that thin paper fed to the 5 cylindrical platen of such machines conforms to the curvature of and usually winds around the platen.

The object of the invention is to provide means for diverting the paper from the platen to the 10 usual paper support plate.

The invention consists in the novel construction and combination of parts, as set forth in the appended claim.

In the accompanying drawings illustrating the 15 invention:

Fig. 1 is a front elevation of a portion of the carriage of a listing calculator, the paper guide being shown in active position.

Fig. 2 is a cross section, taken substantially at 20 the middle of Fig. 1, the paper guide being shown in inactive position.

Fig. 3 is a similar view, the paper guide being shown in active position.

In the drawings, the numeral 1 designates the 25 usual cylindrical platen, supported in the carriage of a listing calculator.

A roll of tally tape paper 2, suitably supported by the carriage, is fed upon platen 1, through slotted opening 3. Paper 2 is held in contact 30 with the platen by means of feed rollers 4, forming part of a guiding assembly 5 located below the platen, the paper passing also beneath guide 6.

The following novel means are provided to prevent the paper 2 from continuing around the 35 platen 1, as said platen is rotated in well known manner, and to divert the paper along the usual carriage back plate 7.

A plate 8 removably supported upon the face of back plate 7 is provided with a suitable slot 40 9 through which extends button 10, secured to

a curved leaf spring 11. Spring 11 extends downwardly along the face of plate 8 and passes through suitable embossments 12 of said plate.

Button 10 is moved downwardly along slot 9 until spring 11 contacts the platen 1, said spring 5 flexing to its normal curved condition as it passes from beneath lower embossment 12 as shown in Fig. 3.

The normal clockwise rotation of platen 1 during a paper feed action will force spring 11 backwards slightly into adjusted position wherein said spring will just contact the surface of platen 1 without exerting pressure thereon.

As paper 2 is fed around platen 1 the forward edge of said paper will now contact spring 11 and 15 be guided upwardly along plate 8, suitable embossments 13 of said plate camming the paper outwardly, to prevent engagement thereof with the embossments 12.

Since full size sheet paper, such as bank statements, etc., are inserted around platen 1 from the face of plate 7 spring 11 is first withdrawn by sliding button 10 to the top of slot 9 the lower embossment 12 acting to straighten spring 11 and hold said spring flatly against plate 8. 20 25

I claim:

The combination with a cylindrical rotary platen of a paper guide comprising a support, a normally curved leaf spring, means to adjustably secure the spring to said support whereby in one 30 adjusted position said spring is flattened against said support in tangential relation to said platen, and in another adjusted position of said spring an end thereof is in engagement with the platen at a point offset from the plane of said tangential 35 relation, said point being determined by the tendency of said spring to assume its curved condition.

LORING PICKERING CROSMAN.
